UNITED STATES PATENT OFFICE.

WALTER J. HERSCHEDE, OF CINCINNATI, OHIO.

DESIGN FOR A CLOCK-CASING.

47,187.

Specification for Design.

Patented Apr. 6, 1915.

Application filed January 8, 1915. Serial No. 1,248. Term of patent 7 years.

To all whom it may concern:

Be it known that I, WALTER J. HERSCHEDE, a citizen of the United States, residing at Cincinnati, in the county of Hamilton and State of Ohio, have invented a new, original, and ornamental Design for a Clock-Casing, of which the following is a specification, reference being had to the accompanying drawing, forming part hereof.

The figure is a perspective view of a clock casing showing my new design.

I claim:

The ornamental design for a clock casing, as shown.

WALTER J. HERSCHEDE.

Witnesses:

WALTER F. MURRAY,
W. THORNTON BOGERT.
